UNITED STATES PATENT OFFICE.

ROBERT O. CROW, OF GOLDSBORO, NORTH CAROLINA.

CLOTHESPIN.

Application filed March 16, 1922. Serial No. 544,197.

To all whom it may concern:

Be it known that I, ROBERT O. CROW, a citizen of the United States, residing at Goldsboro, in the county of Wayne and State of North Carolina, have invented certain new and useful Improvements in Clothespins, of which the following is a specification.

This invention relates to improvements in clothes pins.

The primary object of the invention is the provision of a relatively simple clothes pin, preferably formed of a strand of wire bent to provide a plurality of line engaging arms which are arranged in novel manner for cooperation with a line, whereby articles may be suspended therefrom without liability of accidental detachment, and without the unnecessary wear and liability of tearing of the article suspended, such as is apt to occur with the ordinary types of clothes pins embodying clamping jaws.

A further object of the invention is the provision of a novel type of clothes pin, susceptible of attachment to a line, that the same may remain thereon independent of its supporting an article from said line.

A further object of the invention is the provision of an improved clothes pin of the above mentioned character, which is designed to facilitate ease of attachment to a line, and which may be easily detached from the line.

Other objects of the invention will be apparent during the course of the following detailed description.

In the accompanying drawing, forming a part of this specification, and wherein similar reference characters designate corresponding parts throughout the several views.

Figure 1 is a perspective view of the improved clothes pin, showing the manner in which an operator attaches the same to a line.

Figure 2 is a side elevation of the improved clothes pin, showing the association of parts thereof.

Figure 3 is an end elevation of the improved clothes pin, showing the cooperative association of the line engaging arms thereon.

In the drawing, wherein for the purpose of illustration is shown a preferred embodiment of my invention, the letter A designates a clothes supporting line of any

character, with which the improved clothes pin B is to be associated in the suspension of clothes and other articles.

The line A, may be of rope or wire, suitably tensioned for clothes supporting purposes.

The improved clothes pin B is preferably formed of but a single strand of galvanized spring wire, bent intermediate its ends to provide small and relatively larger U-shaped portions 10 and 11 respectively, lying in the same general plane. The relatively small U-shaped portion 10 is provided with the bight portion 12 having the spring arms 13 and 14 depending therefrom, preferably in parallel relation. It is preferred that the relatively larger U-shaped part 11 comprise the bight portion 15 and the depending spring arms 16 and 17 preferably extending in parallel relation. The U-shaped portions 10 and 11 differ in dimensions both with respect to the spacing of the spring arms thereon, and with respect to the height of said spring arms. Thus, the arms 13 and 14 of the part 10 are spaced for a less distance than the arms 16 and 17 of the portion 11. Likewise, the height of the spring arms 13 and 14 is less than the height of the arms 16 and 17. The portions 10 and 11 are so related, that the spring arms 14 and 16 lie in abutting relation so that said arms 14 and 16, in fact, form but a single spring arm for the improved clothes pin B, as can readily be seen from Figures 1 and 2 of the drawing. Thus, the outwardly extending spring arms 13 and 17 of the portions 10 and 11 respectively form the outer arms of the improved clothes pin B, while the abutting arms 14 and 15 form but an intermediate arm for the clothes pin B.

In order that the end and intermediate arms of the improved pin B may suitably engage the line A, it is preferred that the end arms 13 and 17 be provided with the line receiving crimps 18 and 19 respectively, preferably extending outwardly in the same direction from the plane of the clothes pin B. On the other hand, the intermediate arm formed by the abutting portions of the U-shaped parts 10 and 11 is provided with a crimp 20, which extends outwardly from the plane of the pin B, directly opposite to the extension of the crimps 18 and 19 above noted. The extreme lower end 21 of this intermediate arm is, of course, rounded, due to the fact that this is the

juncture point of the U-shaped parts 10 and 11 of the pin B. On the other hand, it is preferred that the extreme ends 22 and 23 of the outwardly extending end arms 13 and 17 be rounded, as by looping these extreme ends upwardly, so that the marginal edge 24 of each of these end arms may engage the convex side of their respective arm crimps. From this relation of the crimping of the 10 end and intermediate arm portions of the clothes pin B, it can readily be seen that the end arms 13 and 17 of the improved clothes pin are crimped in oppositely extending manner with respect to the intermediate arm.

In the application of the improved pin B to the line A, it is to be noted that the pin B is to be so positioned thereon that the line A engages in the concaved sides of the crimps 18, 19 and 20. This result is effected by the operator first grasping the pin B by the thumb and index finger engaging the abutting arms 14 and 16, just below the bight portion 12. In this relation, the larger U-shaped portion 11 is disposed within the hand of the user, just below the palm, as can be seen in Figure 1 of the drawing. The first operation which is that of straddling the relatively small U-shaped portion 10 over the line A, so that the concaved sides of the crimps 18 and 20 may engage opposite sides of the line A. The end and intermediate arms are of spring material, and of course, will flex. By an 35 angular movement of the hand, the operator then swings the pin B so that the concaved surface of the crimp 19 will engage the same side of the line A, as the crimp 18 above noted. In this manner, the end spring arms 40 13 and 17 will engage the line A upon one longitudinal side thereof, while the intermediate arm defined by the portions 14 and 16 engages the opposite side of the line A. Of course, the concaved sides of the crimps 45 18, 19 and 20, engage the lines A. The spacing of the relatively longer end spring arm 17, for a farther distance with respect to the intermediate arm than the other end arm 13 is spaced, is provided, so that the 50 operator may apply the clothes pin B to the line A with but little exertion. In other words, the end arm 18 and the intermediate arm having engaged the clothes line A, the other spring arm 17 may be applied with but 55 little angular movement, due to the distance which the same is spaced from the intermediate arm. By reason of this arrangement, the clothes pin B will be tensioned sufficiently to hold the same on the line A. 60 It is to be noted that the concavities formed by the crimps 18, 19 and 20, are not in alignment, in so far as the plane of the pin B is concerned, and which can readily be determined from Figure 3 of the drawings. 65 By reason of this arrangement, it is abso-

lutely necessary that the operator relatively flex the end and intermediate spring arms, in order to secure the attachment of the same to the line A for holding an article.

By means of the improved pin B, an 70 article or plurality of articles may be supported by various arms of the pin B. No arms are provided directly opposed to each other for clamping to the line A, since the clothes pin B engages the line A, in so far 75 as the arms are concerned, in staggered manner.

Various changes in the shape, size and arrangement of parts may be made to the form of invention herein shown and described, without departing from the spirit 80 or of the invention or scope of the claims.

I claim:

1. As an article of manufacture, a clothes 85 pin having spring arms extending to provide end arms and an intermediate arm, said intermediate arm being disposed nearer to one of said end arms than the other end arm.

2. As an article of manufacture, a clothes 90 pin formed of spring material bent to provide a plurality of outwardly extending arms to provide end arms and an intermediate arm, said arms extending in parallel relation and having said intermediate arm 95 disposed nearer to one of said end arms than with respect to the other.

3. As an article of manufacture, a wire 100 clothes pin formed of a single strand of material bent intermediate its ends to provide a pair of U-shaped portions of unequal dimensions each having a pair of depending arms spaced at unequal distances, said U-shaped portions so forming said pin as to have an arm of each in abutting relation to 105 provide an intermediate line engaging arm having end arms upon each side thereof.

4. As an article of manufacture, a clothes 110 pin of spring wire material bent to provide a plurality of outwardly extending arms in substantially the same plane, each of said arms having a line engaging crimp formed thereon adjacent its outer end, said crimps being bent in the same direction only upon alternate arms.

5. As an article of manufacture, a clothes 115 pin of wire material bent intermediate its ends to provide a pair of U-shaped portions each including a pair of outwardly extending arms, said arms being crimped adjacent their outer ends for line receiving purposes, adjacently positioned arms being crimped in oppositely extending manner.

6. As an article of manufacture, a clothes 120 pin formed of wire material bent to provide a plurality of spring arms extending in substantially parallel relation in the same direction, said arms being bent adjacent their outer ends to provide arcuate crimps for line receiving purposes, said crimps upon 125

adjacent arms being bent in oppositely extending manner, said arms upon their extreme outer ends being looped to engage the convex sides of said crimps.

5 7. As an article of manufacture, a clothes pin formed of a single strand of spring wire bent intermediate its ends to provide relatively small and larger U-shaped portions, each including arms and a bight portion
10 connecting said arms, said U-shaped por-

tions having an arm of each lying in abutting relation to have said U-shaped portions extending substantially in a common plane, and whereby the arms thereof extend outwardly in parallel relation, said arms being 15 crimped adjacent their outer ends in arcuate manner, whereby adjacent arms of said pin will be crimped in opposite manner for line engaging purposes.

ROBERT O. CROW.
